FORM FOR CONCRETE FLOOR
CONSTRUCTIONWilliam M. Goldsmith and Benjamin Harig,
Cincinnati, Ohio, assignors, by mesne assignments,
to said William M. Goldsmith

Application July 17, 1929. Serial No. 379,021

14 Claims. (Cl. 25—131.5)

This invention relates to temporary forms for use in concrete construction work. In particular, the invention has to do with extensible soffits of the type shown in co-pending application, Serial Number 184,390, of Benjamin Harig. In addition to the soffit, the present invention concerns itself with certain other co-operating members to be used in the construction of a flat surface upon which concrete floor and ceiling slabs may be formed.

An object of the invention is to provide an improved soffit.

Another object is to provide improved forms of filler strips and panels.

Another object is the provision of an improved angle member for supporting filler strips and panels.

These and other objects are attained by the means described herein and set forth in the accompanying drawings, in which:

Fig. 1 is a perspective view of an improved soffit of the present invention attached to a mold, parts of both being broken away.

Fig. 2 is a view taken on line 2—2 of Fig. 1.

Fig. 3 is a perspective view of an angle member of the present invention.

Fig. 4 is a perspective view of a panel of the present invention, in position between a pair of soffits.

Fig. 5 is a view taken on line 5—5 of Fig. 2.

Fig. 6 is a top plan view of Fig. 1, showing, in addition, one of the positioned filler strips of the present invention.

Fig. 7 is a view similar to Fig. 6, but with parts in different relationship.

Fig. 8 is a view taken on line 8—8 of Fig. 7.

Fig. 9 is a view showing a modified use of the filler members of the invention.

Fig. 10 is a top plan view of a portion of a deck or temporary surface constructed with means of the present invention.

Fig. 11 is a perspective view showing a modified form of decking of this invention.

Fig. 12 is a view similar to Fig. 4 and showing a panel of this invention positioned upon a different form of support member.

Fig. 13 is a view similar to Fig. 10 and showing a modified form of decking member of this invention.

This invention comprises a construction of a ceiling and floor slab with or without the ribbed structure which is frequently used and generally accomplished by the use of tiles or domes. In the type of structure now to be explained the slabs are formed integral with and supported

solely by columns and girders, without the addition of joists such as displayed in the above mentioned ribbed structures. In the formation of such slabs it is necessary to provide between the girders or beams temporary flat surfaces or decks upon which the mush or wet concrete may be poured and allowed to harden, after which the temporary decking is removed.

Improved means for forming this decking are provided by the present invention. Briefly, these means include extensible or adjustable soffits which extend between the beams, panels which extend between the soffits and certain smaller members which fill the interstices occurring between the soffits and beams and between the panels and the beams, by which means a solid deck may be constructed upon which to form the desired slab.

With reference to the drawings a suitable mold 12, having base 13 and opposed sides of the character of side 14 (Fig. 1) is developed for forming the concrete beams. A board 15, known as a batten, is secured to the mold board 14, such battens being provided at intervals along board 14. An edging 16 may be fastened to the upper edges of boards 14 and 15, said edges being disposed in the same plane. Supports or ribbon boards 17 are secured to boards 15 adjacent the tops thereof and at equal distances from strip 16. The molds 12, thus formed, are now adapted to receive and support the soffits which are to extend between the beams.

The soffits 18 of the present invention may be constructed of suitable boards and comprise the upper or table member 19 to the lower face of which the joist or brace 20 is secured at substantially right angles thereto, and extending longitudinally of the center thereof. Brackets or other suitable supporting means 200 may be secured to the sides of brace 20 and to the under face of member 19. Brace 20 is of a greater length than member 19, the ends 21 of brace 20 extending outwardly beyond the ends of member 19. Spacers or shims 22 are fixed between the under face of member 19 and the upper edge of brace 20, so that the space 23 results therebetween. The ends 21 of brace 20 have the straps 25, preferably of metal, secured thereto by suitable nails or screws 26. The upper section 27 of strap 25 extends within the space 23. The opposite end 28 of strap 25 is secured against the lower edge of brace 20. Adjacent the lower edge of brace 20, the strap 25 is formed to provide the sleeve 29 providing the way 30 extending transversely of the end of brace 20 (Fig. 5).

The extension members 31 may be formed of metal and are U-shaped in cross section. They comprise sides 32 and 33 and top 34. The end portions 35 of sides 32 and 33 are bent outwardly 5 substantially at right angles to sides 32 and 33, as indicated at 36 (Fig. 1). An arm 37 formed by an extension of top 34 is severed from connection with the portions 35 and extends forwardly thereof. An angle plate 38 having a right 10 angle flange 39 is secured to the portion 35, the main body of the plate abutting the front faces of portions 35, and the upper face of flange 39 being in abutment with the lower face of arm 37. Aligned slots 40 in sides 32 and 33 extend 15 longitudinally of extension member 31. Extension 31 cooperates with soffit 18 by having its top 34, at the free end thereof, projected into the space 23, the top 34 being seated and slideable upon section 27 of strap 25 (Fig. 5). The positioning of extension member 31 aligns the way 30 20 of sleeve 29 with the slots 40, so that a pin 41 may be inserted through way 30, its ends projecting outwardly beyond sides 32 and 33 of the extension 31, and having perforations 42 for receiving suitable cotter pins 43 which prevent withdrawal of pin 41. A bolt 44 passing through brace 20 and slots 40 is provided with a wing nut 45 which can be tightened for frictionally holding the extension member 31 in a given position 25 relative to brace 20. Extension member 31 is thus adjustable longitudinally of brace 20, outward or forward movement thereof being limited by the abutment of ends of slots 40 upon the bolt 44. The pin 41 prevents any sagging or 30 pivotal movement of extension 31 about bolt 44 that might otherwise occur upon the application of weight to the table member 19. The strap 25 prevents wearing and splintering of the end of brace 20, due to repeated adjustments of extension 31 thereon.

The angle members 46 may be substantially Z shape and comprise a body or plate portion 48, a ledge or supporting lug 49, a web portion 51 and a tongue 50 extending from the plate portion 48 in the same plane therewith and directly above and parallel with ledge 49. The tongue may be so formed from the web and ledge portion that a connector portion 490 is provided in the ledge joining one lug to the next. The angle members may be elongated as shown at 45 47. The supporting lugs 49 and tongue may be formed integral with plate portion 48 by bending alternate severed portions of the metal along one side of plate 48 into L shape, so as to provide sections 51 disposed at right angles to plate 48, and sections 49. The tongues 50 occurring between the lugs 49 are unbent severed portions of plate 48. Perforations 53 are provided in the angle member.

Decking panels 54 are constructed by inserting opposite sides of a suitable section of boards or paneling material between the sections 52' and tongue 50' of angle strips 47, the edges of the paneling being in abutment against web sections 55 51 (Fig. 4). The panels 54 are so constructed that one or more of them has a length equivalent to the length of the table members 19 upon which the angle strips 47 of the panels are to be secured, as will be shown. Uniformity in manufacture and in use is thus attained.

As illustrated in Fig. 11, thin sheets or panels 540 of rigid metal, such as sheet iron, may be substituted for panels 54, in which case angle strips 47 are rendered unnecessary, as will be 70 explained.

Filler blocks or strips 55 each comprise an angle bracket 46 and a piece of board 56, of a length equal to the projection of an extension member 31 beyond the table 19, when the extension is in its contracted position. Both bracket 46 and board 56 are of a width equal to that of the table members 19 of the soffit with which the filler block is to be used. The longer filler strip 57 (Fig. 10) consists of a section of board having an angle strip positioned along one longitudinal edge thereof. Cross bridge 570 (Fig. 9) is made up of a board having brackets 46 disposed at each end thereof.

In the construction of all the above members, nails or other fastening means 58 are inserted through perforations 53 into the material forming the member. Two sets of perforations 53 may be provided, one set adjacent the front, the other adjacent the rear of plate 48, as shown by the filler strips herein. The use and cooperation of the various parts for constructing a deck will now be described.

It is understood that such a deck is constructed in the space occurring between spaced beams or upon shoring supporting the decking between adjacent columns. A number of soffits are positioned in parallel relation between beams or within such a space as that just described. The positioning of the soffits on beam molds, as shown herein, is accomplished by adjusting the extension members 31 at the ends of the soffits so that the flanges 39 of plates 38 rest upon the upper surfaces of supports 17, whereupon nails are driven through perforations 390 in portions 35 and plate 38, into supports 17. By reference 105 to Fig. 1 it will be seen that an opening results between the ends of the table members 19 and the sides 14 of the mold. These spaces or openings are bridged by the filler blocks 55 as illustrated in Figs. 6, 7 and 8. The plate 110 portion 48 of an angle bracket 46 is secured to the end portion of a table member 19, after the edge of filler piece 56 has been brought into abutment against the side 14 of the mold adjacent and on a level with the top edge of side 14, 115 which edge, as shown, consists of the ribbon strip 16 (Fig. 8). In case it has been necessary to extend the member 31 to its limit in order to properly position the soffit, the greater space thus resulting can be closed by advancing the 120 filler block 55 outwardly of the end of table member 19 until the filler abuts the edging 16 of the girder mold. It is likewise evident that all intermediate adjustments of extension 31 and the resultant openings, are taken care of by 125 the filler blocks and strips of this invention. The filler piece 56 of the filler block is supported over the top 34 of extension 31. The tongue 50, in all the devices described herein, assures the rigid retention of the boarding between the 130 lugs and the tongue, prevents sagging and likewise serves as a positive means against buckling or vertical upward displacement of the positioned member.

When the soffits and filler strips 55 are in 135 position, panels 54 are placed by securing the plate portions 48' of angle strips 47 to the opposed side portions of table members 19 of a pair of soffits. A panel or a number of them placed in lateral abutment, reach from end to end of the table members 19. Thus at the ends of the paneling, a space or opening results between the soffits, equal in width to the distance from the ends of members 19 to the adjacent beam molds. Such spaces are filled by the larger 140 145 150

filler strips 57 which are positioned along the lateral edge of the panel 54 adjacent the beam mold. Filler strips 57 are adjustable on their panels in the same way that fillers 55 are adjustable on members 19, so that when extensions 31 are moved outwardly, the greater space resulting between the beam mold and the panel may be closed by the same filler strips 57. This, as well as the relationship of the positioned parts, will be seen by reference to Fig. 10 which shows a portion of a completed deck in readiness to receive the wet concrete.

A modification 550 of filler strip 57 is illustrated in Fig. 13. By comparison with filler 57 (Fig. 10) it will be seen that filler 550 obviates, in certain instances, the use of filler blocks 55. This is accomplished by making filler 550 of a length sufficient to span the distance between the remote side edges of table members 19 of a pair of adjacent soffits. The ends of filler 550 rest upon the ends of table members 19, the body portion thereof being supported upon the edge of panel 54. Thus a single member may be substituted for the three members illustrated in Fig. 10.

In some instances in the course of a given piece of construction, it may be desirable to provide a cross support at a distance intermediate the ends of the regular soffits. In such and in similar cases, cross bridges 570 may be used to advantage. As seen in Fig. 9, one of brackets 48 of two such cross bridges may be secured to a single support or soffit 90, by superimposing one of the plates 48 upon the other. Cross bridges such as 570 are particularly intended for use in decking on which a rib and slab floor and ceiling structure is formed, for example as shown in the aforesaid Harig application.

As set forth in Fig. 12, panels 54 may be used in the same way as cross bridging 570, that is, upon a single support member 90 providing only a limited supporting surface. In this instance, the plate portions 48 of angle strips 47 are superimposed one upon the other, in positioning sections of the panel.

The invention disclosed herein is not limited to structures comprising beams and girders, but is also adaptable to constructions of the type shown in the patent to Smulski, No. 1,233,529, in which the pillars or columns support the floor slabs and in which shoring is used for supporting the soffits as distinguished from the beam mold 12 and ribbon board 17 shown in Fig. 1 herein.

The invention is not confined to structures wherein a soffit comprises a body or brace member 20 and a table member 19, but is also applicable in cases where the soffit consists only of a member such as 20, and no table member is provided. This type of structure is disclosed in Fig. 9, where the soffit is designated 90. In such forms of construction the panels 54 may be used for providing so-called solid decking; or the panels may be dispensed with for providing so-called open centering. The cross bridges 570 would ordinarily be used only with the open centering type of structure, and with suitable tiles or pans for providing a rib and slab construction. In some instances, the adjustable soffits, without table members, may be installed, and sheathing or flooring lumber laid directly on the soffits, thereby obviating use of the panels 54, and the filler strips would be supported on the sheathing or flooring.

This type of paneling is illustrated in Fig. 11. As previously stated, panels 540 consist of thin,

rigid metal sheets, their side portions resting directly upon the table members 19 of the soffits. Panels 540 extend beyond the ends of table members 19 and abut the supporting beam so that use of the fillers 57 or 550 is obviated. To fill the spaces resulting adjacent the beam between one of the panels 540 and the panels laterally adjacent thereto, the fillers 55 may be utilized. These are placed upon the ends of table members 19 before the positioning of panels 540.

What is claimed is:

1. A soffit comprising a table member, a joist or brace member secured thereto at substantially right angles therewith, a strap member secured to the end and adjacent side edges of the brace at each end thereof, said strap providing a sleeve extending transversely of the end edges of the brace adjacent the lower portion thereof, extension members receivable one each upon each end of the brace, each extension member having slotted sides and a base slidable upon said strap, the slots of the sides being aligned with said sleeve, a pin passing through the sleeve and slots and means passing through the brace and slots and spaced from the pin, for adjusting the extension on the brace.

2. In combination, a soffit comprising a table member and a brace element attached to a surface thereof at substantially right angles thereto and extensible beyond the ends of the table member, and a filler strip adapted to seat upon the upper edge of the extensible portion of the brace and in attachment with the end of the table member, said filler strip comprising a flat element of the same width as the table member and having secured to one edge an angle member with a plate extending therefrom in substantially the same plane as the upper surface of the flat element, the plate being securable upon the end portion of the table member in adjustable positions such that the length of the table member of the soffit may be made equal to the variable lengths of the brace member.

3. A deck panel for use with temporary construction forms and comprising a rectangular, flat element, an angle strip secured to opposite sides thereof, said angle strip comprising a plate portion disposed in substantially the same plane as a surface of the flat element and adapted to be secured to supporting elements of a temporary construction, and means integral with the plate and disposed on the opposite surfaces of the panel along the edge for supporting and preventing vertical movement of the positioned panel.

4. The combination with a pair of girder molds in spaced parallel relation, of soffits disposed between the molds in parallelism, each soffit comprising a table member adapted to be horizontally positioned and brace means secured thereto at right angles therewith and extending beyond the ends of the table member, the brace having extensible elements at the ends thereof, said elements being secured to the girder molds for positioning the soffits, panel means substantially filling the space between a pair of positioned soffits, said panel means comprising a rectangular flat member having angle strips secured to opposite sides thereof and adapted to be fastened to the positioned soffits, and filler strips comprising flat elements with angle strips thereon, said filler strips being secured to the positioned soffits and panels adjacent the girder molds for filling interstices between the girder molds and the positioned soffits and panels.

5. An angle member comprising a plate portion, lugs extending from the plate at one side thereof and in spaced parallelism therewith, tongues secured to the plate in substantially the same plane therewith and extending over the lugs at intervals along the plate, and connector means joining one lug to the next. 80
6. A filler strip for use with temporary construction forms and comprising a board and an angle strip positioned along a longitudinal edge thereof, said angle strip comprising a plate adapted to be secured to a supporting element of a temporary construction, and means integral with the plate and abutting the edge and adjacent surfaces of the board for supporting the board. 85
7. A cross bridge for use with temporary construction forms and comprising a board, an angle member at each end thereof, said angle member comprising a plate portion extending outwardly of the end of the board and tongue and lug portions integral with the plate and lying against the opposite sides of the end of the board. 90
8. A cross bridge for use with temporary construction forms and comprising a board, an angle member at each end, said member comprising a plate portion extending outwardly of the end of the board and adapted to be attached to a supporting member of a temporary construction, and means integral with the plate for supporting the board and preventing vertical upward displacement thereof. 100
9. Temporary decking means for use in connection with spaced beams or girder forms and comprising spaced soffits supported by the girder forms, sections of rigid paneling supported upon the soffits and abutting the girder forms, and means attachable to the ends of the soffits for filling the spaces there resulting between one section of paneling and the sections adjacent thereto. 110
10. The combination with spaced beam or girder forms of temporary decking means comprising spaced soffits attached at their ends to the beam, said soffits providing table members disposed in spaced, endwise relation to the beam, paneling positioned between and supported by the soffits and co-extensive in length with the table members, and a filler member comprising a flat element having means thereon for attachment to the ends of the paneling and the table members whereby to fill the space between the beam form, the paneling and the table members. 120
11. The combination of spaced main support members, spaced extensible soffits supported at their ends by the main support members, each extensible soffit comprising a table member and an extension member, each table member adapted to have its one end disposed at variable distances from one of the main support members, said variable distances being determined by the projection of the extension member beyond the table member when the soffit is supported by the main support members, a filler block between the main support member and that end of each table member spaced from the main support member, each filler block comprising a plate and a block member attached thereto, the plate extending between the block member and the table member and with said block and table members providing a substantially even upwardly exposed face for the entire length of each extended soffit, and means closing the spaces between adjacent soffits and the filler blocks supported thereby. 130
12. The combination of spaced main support members, spaced extensible soffits supported at their ends by the main support members, each extensible soffit comprising a table member and an extension member, each table member adapted to have its one end disposed at variable distances from one of the main support members, said variable distances being determined by the projection of the extension member beyond the table member when the soffit is supported by the main support members, a filler block between the main support member and that end of each table member spaced from the main support member, each filler block comprising a plate and a block member attached thereto, the plate extending between the block member and the table member and with said block and table members providing a substantially even upwardly exposed face for the entire length of each extended soffit, closure means of the approximate lengths of the unextended soffits supported between the spaced soffits, and other filler blocks comprising block members and plate members, extending between the main support member and the closure means, the block members thereof supported by the main support member and the plate members thereof supported by the closure means, the plate members and block members having substantially even upwardly exposed faces in substantial continuity with the upwardly exposed faces of the first mentioned filler blocks, said last mentioned filler blocks closing the spaces between the adjoining first mentioned filler blocks, closure means and main support member. 140
13. The combination of spaced soffits, the soffits comprising table and extensible members, means for supporting the soffits in variable degrees of extension whereby the extensible members may project beyond the table members and whereby openings may be developed between the support means and table members, filler strips insertable in the openings between the soffit tables and the support means and adaptable to various sized openings at the ends of the table members for providing an upper face substantially continuous with the upper faces of the tables, and means including cross bridging supported along adjacent soffits, and forming closures between adjacent soffits and filler strips, said means having their upper faces in substantial continuity with the upper faces of the soffit tables and filler strips. 150
14. The combination with an extensible soffit comprising a table member and an extension member, the table member being disposed above the extension member whereby upon projection of the extension member an offset is provided at the end of the table member and over the extension member, of a filler block comprising a strip member adapted to be supported upon the extension member, and a plate member projecting from the strip member and projecting over the table member whereby a substantially continuous face is provided by the table and the filler block throughout the entire length of the extended soffit. 160
